CLAIM

The ornamental design for a circular light structure, as shown and described.

DESCRIPTION

FIG. 1 is a side view parallel to the axis of the support arms of an exemplary circular light structure;

FIG. 2 is a side view perpendicular to the axis of the support arms thereof;

FIG. 3 is a top plan view thereof;

FIG. 4 is a bottom plan view thereof;

FIG. 5 is a bottom perspective view thereof; and,

FIG. 6 is a top perspective view thereof.

The stem below the center post of the circular light structure of FIGS. 1, 2, 5 and 6, the interior of the center post of the circular light structure of FIGS. 3–6, the cap at the upper end of the center post of the circular light structure of FIGS. 1–2, 5 and 6 (all shown in phantom) do not form a part of the design.
